ALEIN MARIE MAURICE COLLON, OF LYON, FRANCE

WARP STOP MOTION FOR LOOMS FOR WEAVING

Application filed January 7, 1931, Serial No. 507,238, and in France February 2, 1930.

This invention relates to improvements in warp stop motions for looms for weaving.

Electric stop motions operating through the healds are becoming more and more used on looms for weaving at the present time.

The different arrangements based on this principle have numerous advantages over the other types of stop motion these advantages are amongst others that it occupies 10 a minimum space, does not require any supplementary work at the time of inserting the warp in the loom, it will operate when a stoppage is produced or in other words a locking of two or more threads as well as 15 when through clumsiness the overseer leans incautiously on the line of warps at the back of the loom.

All the different types of warp stop motions operating on this principle are subject 20 to the numerous inconveniences in practice as they all necessitate a regulating system either of oscillating members or of connections and stops between the loom and the healds. In use, remembering that the movements of the healds are very abrupt these members rapidly become deranged the stops break down, giving an uncertain operation, consequently defective. On the other hand, the poor operation of this system of warp 25 stop motion is often caused by the plates which are very light being damaged either at the time of piecing up the threads or owing to the operation itself of the stop motion. It follows that they will not move freely 30 to open or close the electric circuit.

The present invention relates to a warp stop motion operated by the healds of the loom and overcoming the aforesaid disadvantages since once it is operating on the 40 loom it does not require any adjustment as it does not comprise any connecting link between the heald and the loom. Further to each lifting heald frame the plates which would be damaged or buckled are automatically straightened,

It is furthermore obtainable at a very low price.

It is essentially characterized in that the 50 rod carrying the lower ends of the healds which is rigidly affixed to an electric con-

ductor kept at a given distance from the said rod by electrically insulating supports is suspended without other connection at the healds and frame and may be displaced parallelly to itself inside this latter under the 55 action of the tension of the warps when the healds are in their lower position.

It will be readily understood that in this position when there is a breakage of a warp or when a holding or catching occurs the 60 corresponding heald is not drawn upwards by its thread and its lower and contacts with the aforesaid conductor due to its weight and thus through any suitable trip mechanism 65 stops the loom.

The invention will be described with reference to the accompanying drawing:

Fig. 1 is a front view of a heald frame in its lower position.

Fig. 2 is a side view.

Figs. 3 and 4 are corresponding views showing it in the raised position.

According to the invention in each heald frame or element the lower bar *a* is suspended by the loops *b*² from the healds *b* suspended in their turn by loops *b*¹ from the upper bar *c* which is rigidly affixed to the frame *d*. The lower bar *a* aforesaid is thus free to be moved vertically between the ends of the frame.

This bar *a* is rigidly connected by supports *e*¹ to an electric conductor *f* in circuit through a flexible lead *g* with one of the terminals of a source of electric supply.

These supports *e* which hold the conductor *f* at a strictly constant distance from the lower bar *a* and which follow all the movements are electrically insulated at *h* so that during the normal operation the electric current cannot pass from the conductor *f* to the frame *i* through the bar *a*.

Rods *j* to the stops *k* pass through the transverse member *l* of the frame to limit the upward movement of the healds and the bars *a* and conductor *f* under the tension of the warps *m* passing through eyelets *n* in the healds *b* when heald frame is in its lower position.

The operation of such an arrangement will 100 be readily understood.

In normal operation when the heald frame is in its raised position (Figs. 3 and 4) the tension of the warps *m* is exerted downwards on the healds *b* holding these latter in conjunction with their weight suspended by their upper loops *b*¹ from the upper bar *c* rigidly affixed to the frame *d*. In this position, the movable bar assembly *a* and the electric conductor *f* are also suspended by their weight 5 from the lower loops *b*² of the healds. The loops *b*² are utterly prevented from contacting with the conductor *f*. Further in this position any heald which is faulty or buckled and due to this fact shorter than the rest 10 itself carries the whole weight of the assembly *a* of which tends to correct it.

On the contrary, when the heald frame moves to its lower position (Figs. 1 and 2) the tension of the warps *m* is exerted upwards and raises all the healds to which remain suspended in the lower loops *b*² the bar *a* and the conductor *f*. This raising movement is limited by the stops *h* coming in contact with the lower transverse member 20 *i* of the frame.

Thus, in this position, if a warp such as *m*¹ is broken the corresponding heald *b*¹ which is no longer held upwards remains suspended owing to its weight by the upper loop *b*¹ 30 from the bar *c* and its lower end *b*¹² comes in contact with the conductor *f* which immediately connects this latter to the earthed member *i* and thus causing through suitable tug mechanism, stops the loom.

35 The same thing occurs if instead of a breakage of a warp there is a drawing of this latter downwards as would be produced by a holding or catching thereof.

As will be understood and as follows from 40 what has preceded the invention is not limited either to the single method of operation described above or to its different parts but embraces on the other hand all variations comprising the application of the above arrangements.

Having now particularly described and ascertained the nature of our said invention and in what manner the same is to be performed, I declare that what I claim is:

50 In an electric warp stop motion for looms, the combination of a frame carrying the heddles and having a lower bar movable vertically with respect to the frame, and an electric conductor bar arranged below, parallel 55 with and rigidly connected to said lower bar for movement therewith, so that upon the breaking of a warp thread, its heald drops into contact with the conductor bar and completes an electric circuit, said frame having a 60 lower transverse member, and the lower heald bar and the conductor bar being provided with rods connecting them together, said rods being insulated from the conductor bar and movable vertically through said 65 lower transverse member and provided with

stops to limit the extent of relative vertical movement of said lower heald bar and said conductor bar.

In witness whereof I have hereunto set 70 my hand.

ALBIN MARIE MAURICE COLLON.
